FIG. 1

FIG. 2

FIG. 3

FIG. 4

FIG. 1 is a front, right side and top perspective view of a dual tube television receiver, or similar article, showing our new design, wherein the tubes are aligned horizontally on the front panel.

FIG. 2 is a front view of the television receiver shown in FIG. 1.

FIG. 3 is a right side view of the television receiver shown in FIGS. 1 and 4.

FIG. 4 is a front, right side, top perspective view of a modified form of the dual tube television receiver design of FIG. 1, wherein the tubes are aligned vertically on the front panel.

The opposite sides of FIGS. 1 and 4 are mirror images of the side shown while the back is conventional in appearance. An optional polarizing screen is shown in broken lines in FIGS. 1 and 4.

We claim:

The ornamental design for a dual tube television receiver or similar article, as shown and described.
